COVER FOR TOILET FLUSH TANKS

Paul E. Doebler, Monroe, Ohio

Application February 7, 1951, Serial No. 209,883

4 Claims. (Cl. 150—52)

1

This invention relates to a cover for a toilet flush-tank for the purpose of eliminating moisture condensation on the exterior of the tank and the resultant dripping of the moisture therefrom.

It is the object of the present invention to provide a cover for a toilet flush-tank formed of a waterproof fabric sheeting which is adapted to be mounted around the lateral walls of the tank in a loose manner to provide an insulating layer of air around the exterior of the tank in order to eliminate condensation of moisture either on the exterior of the tank or on the cover, resulting from the filling of the tank with cold water in a humid or warm atmosphere in which the tank is disposed.

It is another object of the invention to provide a cover for a toilet flush-tank of plastic fabric or sheeting which may be clear, colored or patterned to blend in with the ornamentation of the rest of the bathroom in conformity with the ensemble effects generally obtained by the window and shower curtains in a bathroom, in order to carry out more completely the desired ornamental effects, while effectively arresting any dripping of condensate onto the bathroom floor, which gives rise to unsightly puddles on the floor and eventual damage to the floor or floor covering.

It is another object of the invention to provide a cover of plastic sheeting which may be applied to the lateral walls of a toilet flush-tank in a ruffled or bloused state, without any special tools or special connections. The cover extends neatly around the lower part of the tank and at least beyond the upper level of the water in the tank in order to eliminate the condensation of moisture on the tank exterior arising from the entry of cold water thereto.

It is another object of the invention to provide a flush tank cover of plastic sheeting which is economical and simple in construction, which is adapted to fit tanks of different sizes, which is readily interchangeable to vary the ornamental effects in the room and which may be laundered for repeated use as easily as are shower and window curtains.

The invention proceeds upon the principle of mounting a cover of plastic sheeting around the three lateral exposed walls of a toilet flush tank, which cover is ruffled along its longitudinal dimensions by being strung on a pair of horizontally extending elastic tapes. The elastic tapes may be stretched between the upper and lower ends of vertical anchor wires which may be held onto the side walls of the tank by suction

2

cups, in close adjacency to the building wall against which the tank is mounted. The upper tape, preferably extending along a level above the water level in the tank, is run through an upper heading of the plastic sheeting, which may be formed by heat sealing, and is of shorter length than the plastic sheeting in order to effect a ruffling of the latter as the same is passed around the two side walls and front wall of the flush tank. A lower tape is passed through a lower heading on the cover which is adapted to embrace the three peripheral edges of the bottom of the flush tank in order that the ruffles may extend to the bottom wall of the tank without showing the lower tape. A variable stretching of the elastic tapes permits the cover to surround tanks of different dimensions. The consequent ruffling of the plastic cover results in an irregular dead air space of small extent between the cover and the lateral walls of the flush tank, which acts as an insulating layer between the cold water in the tank and the atmosphere, as a result of which no condensation may take place either on the exterior of the tank or on the cover with the subsequent dripping of moisture therefrom.

Other objects and purposes will appear from the detailed description of the invention following hereinafter, taken in conjunction with the accompanying drawing, wherein:

Fig. 1 is a front view of a toilet flush tank having the cover in accordance with the invention mounted thereon, with a fragmentary portion of the cover and tank broken away in order to show the effective field of operation of the cover;

Fig. 2 is a right end view of Fig. 1;

Fig. 3 is a bottom view of Fig. 1;

Fig. 4 is a front elevation of the face of the cover looking upon the side thereof which is adjacent to the toilet flush-tank;

Fig. 5 is a vertical sectional view along line 5—5 of Fig. 4 to show on an enlarged scale a preferred mode of attachment of the ends of the cover to the toilet flush-tank; and

Fig. 6 is a vertical sectional view along line 6—6 of Fig. 4.

In the drawings is shown a toilet flush-tank T, which may be of conventional construction, provided with a water inlet pipe I and an outlet pipe O in the bottom thereof for the purpose of filling it with water up to a water level L as controlled by a conventional float F, and discharging the water through the pipe O, as controlled by a handle H, as is common in such plumbing fixtures.

In warm and humid weather, the entry of cold water into the tank causes a condensation of the moisture in the surrounding atmosphere on the exterior walls of the tank, which under humid conditions results in a dripping of the condensate from the exterior walls of the tank onto the bathroom floor. Many expedients have been tried to eliminate the untidiness resulting from this dripping, and resort has been made to absorbent pads or pans on the exterior of the tank, or insulating liners on the interior thereof. However, these have proved both expensive and ineffective.

In accordance with the applicant's invention, a cover C of waterproof fabric, preferably plastic sheeting, is bloused or ruffled onto the three exposed sides of the tank in order to form a heat insulating air layer around the parts of the tank on which condensation normally takes place, whereby the cold water on the inside of the tank is incapable of exercising its condensation effects on the atmosphere surrounding the tank, and no accumulation of moisture takes place with the resultant dripping thereof onto the bathroom floor or floor covering.

The cover C of plastic fabric is formed of a piece of continuous sheeting which is adapted to be shaped with a front portion 10 and two side portions 11 and 12, and exceeds in length the peripheral dimensions of these walls of the tank. Upper and lower headers 13 are formed on the plastic sheeting by folding over the upper and lower edges thereof and heat sealing the extremities of the folded edges with the cover at seams 13'. Lateral headers 14 are likewise formed at the lateral ends of the cover by the heat sealing of the seams 14'. Vertical wires 15 are extended through these lateral headers 14 and are looped near the opposite ends thereof at 17 to embrace the bases of suction cups 16 thereat. The ends of each of the wires 15 are formed with eyes 18. An elastic band 20 is passed through the upper header 13 and is attached to the oppositely disposed top set of eyes 18. This attachment may be by stitching 19 or in any other suitable manner. Similarly another elastic band 20 is passed through the lower header with the opposite ends thereof fastened to the bottom set of eyes 18 by stitching 19 or otherwise. The length of the cover is in excess of the length of the tapes 20 so that the cover may be strung on the tapes with a ruffled or bloused effect even when the tapes are in extended position as is the case when the upper tape is passed around the three external walls of the tank, and the lower tape is stretched around the bottom periphery of the tank. The cover is mounted on the tank by affixing the anchoring wires 15 on the sides of the tank in close adjacency to the building wall W by means of the suction cups 16 and by simply stretching the cover around the tank through the intermediary of the two elastic tapes as described above.

Since the upper end of the cover is below the handle H and the lower boundaries of the cover merely surround or overlap the edges of the bottom of the tank, no cut-outs for any of the plumbing fixtures need be provided in the cover. The same may be detached from the tank very easily by simply disengaging the vacuum cups.

The cover may be washed while the same is in operative position or may be detached for washing with or without the removal of the anchoring wires and vacuum cup retainers therefrom.

In view of the low cost of construction of the cover, the same may form a component part of bathroom ensembles for interchangeable use with different sets of shower and window curtains of different colors and patterns.

While I have described my invention as embodied in a specific form and as operating in a specific manner for purposes of illustration, it should be understood that I do not limit my invention thereto, since various modifications will suggest themselves to those skilled in the art without departing from the spirit of my invention, the scope of which is set forth in the annexed claims.

I claim:

1. A cover for a toilet flush-tank formed of a continuous sheet of waterproof fabric adapted to extend around the exposed lateral vertical walls of the tank, seamed headers along the upper and lower edges of said cover, elastic tapes extending through said headers, said tapes being of shorter length than said cover whereby a ruffling effect is imparted to said cover to produce thereby an air space between the cover and the vertical walls of the tank, and means for anchoring the opposite ends of said elastic tapes onto the extremities of the lateral walls of the flush-tank at different levels thereof.

2. A cover for a toilet flush-tank formed of a continuous sheet of waterproof fabric adapted to extend around the exposed lateral walls of the tank, seamed headers along the upper and lower edges of said cover, elastic tapes extending through said headers, said tapes being of shorter length than said cover whereby a ruffling effect is imparted to said cover, seamed vertical headers at the opposite ends of said covers, a wire extending through each of said vertical headers, suction cups retained by said wires for mounting on the ends of the lateral walls of the tank, and fastening means between the ends of said tapes and said wires.

3. A device as set forth in claim 2 wherein said fastening means comprises stitching on said elastic tapes embracing the ends of said wires.

4. A cover for a toilet flush-tank formed of a continuous sheet of plastic fabric adapted to extend around the exposed lateral walls of the tank, coalescently seamed headers along the upper and lower edges of said cover, elastic tapes extending through said headers, said tapes being of shorter length than said cover whereby a ruffling effect is imparted to said cover, coalescently seamed vertical headers at the opposite ends of said covers, a wire extending through each of said vertical headers, suction cups retained by loops in said wires for mounting on the ends of the lateral walls of the tank, and stitched fastening means between the ends of said tapes and said wires.

PAUL E. DOEBLER.
